UNITED STATES PATENT OFFICE.

WILLIAM M. PETTY, OF DENVER, COLORADO.

DESIGN FOR A RADIATOR ORNAMENT.

Application filed February 17, 1928. Serial No. 25,475. Term of patent 3½ years.

To all whom it may concern:

Be it known that I, WILLIAM M. PETTY, a citizen of the United States, residing at the city and county of Denver and State of Colorado, have invented a new, original, and ornamental Design for Radiator Ornaments, of which the following is a specification, reference being had to the accompanying drawings, forming part thereof.

Fig. 1 is a top plan view of a radiator ornament showing my new design;

Fig. 2 is a side elevation; and

Fig. 3 is a front end elevation.

I claim:

The ornamental design for a radiator ornament, as shown.

In testimony whereof I affix my signature.

WILLIAM M. PETTY.
